Inventor

Frederick Greer,
By Chas. C. Bulkeley,

UNITED STATES PATENT OFFICE.

FREDERICK GREER, OF CHICAGO, ILLINOIS.

DESIGN FOR A PROTECTOR AND FUSE HOLDER AND BLOCK.

SPECIFICATION forming part of Design No. 30,634, dated April 25, 1899.

Application filed April 1, 1899. Serial No. 711,450. Term of patent 7 years.

To all whom it may concern:

Be it known that I, FREDERICK GREER, a citizen of the United States, residing at Chicago, in the county of Cook and State of Illinois, have invented a certain new and useful Design for a Protector and Fuse Holder and Block, of which the following is a description.

My invention relates to a new design for protector and fuse holder and block illustrated in the accompanying drawing, wherein the figure is a perspective view of a protector and fuse holder and block embodying my design.

The protector and fuse holder and block consist of the base A, provided with a cut-out portion or cavity B at one end thereof, having the side flanges B² and the rounded projection B³, together with the upright post

B⁴ and the extended strips B⁵. The flat top portion D of the base has therein the recesses 20 or cavities D², circular in form, and the upwardly-extended and meeting pieces D³, arranged in pairs and projecting in pairs upwardly from a common base-piece D⁴.

The essential features of my device are embodied in the description as set forth.

What I claim is—

The design for protector and fuse holder and block substantially as hereinbefore described and as shown in the drawing. 30

In testimony whereof I affix my signature in presence of two witnesses.

FREDERICK GREER.
